UNITED STATES PATENT OFFICE.

WALLER E. PEARL, OF SEDALIA, MISSOURI.

DENTAL INSTRUMENT.

1,368,195.

Specification of Letters Patent.

Patented Feb. 8, 1921.

Application filed July 8, 1918. Serial No. 243,872.

To all whom it may concern:

Be it known that I, WALLER E. PEARL, a citizen of the United States, residing at Sedalia, in the county of Pettis and State of Missouri, have invented a new and useful 5 Dental Instrument, of which the following is a specification.

This invention relates to dental instruments one of its objects being to provide 10 means for rotating delicate reamers and the like in the root canals of posterior teeth, the device being hand operated and transmitting rotary motion at a right angle.

A further object is to provide an instrument of this character which is of light 15 weight, gives the operator a delicate sense of touch and occupies very little space in the mouth so as to obstruct the vision of the operator.

20 A still further object is to provide an instrument which will not slip from the hand and become lodged in the throat of the patient and also one which will permit the use of a mouth mirror while cleaning or reaming the canals in posterior teeth.

Another object is to provide an instrument in which the power is transmitted directly from the driving shaft to the head of the reamer or other tool, thereby saving 30 valuable space and reducing the weight of the instrument.

With the foregoing and other objects in view which will appear as the description proceeds, the invention consists of certain 35 novel details of construction and combinations of parts which will be hereinafter more fully described and claimed, it being understood that various changes may be made in the construction and arrangement 40 of the parts without departing from the spirit or sacrificing any of the advantages of the invention as set forth in the appended claims.

In the accompanying drawings the preferred form of the invention has been shown.

45 In said drawings

Figure 1 is a side elevation of the instrument.

50 Fig. 2 is a longitudinal section there-

Fig. 3 is an end view.

Fig. 4 is a detail view of the latch.

Referring to the figures by characters of 55 reference, 1 designates the tubular casing of the instrument one end of which is counterbored as at 2 and interiorly screw thread-

ed while the other end terminates in a short elbow 3 having a slot extending thereinto and partly thereacross, as shown at 4, said slot lying in a plane parallel with the free 60 end of the elbow, and parallel with the longitudinal axis of the casing 1. This slotted portion of the elbow is closed except for a small opening 5 extending thereinto at right angles to the axis of the casing 1. 65

A drive shaft or spindle 6 is mounted for rotation in the casing 1 and has a collar 7 bearing in the counterbore 2, said collar being held in position by a threaded sleeve 8 extending into the counterbore from a 70 milled nut 9 located on the end of the casing. A knob 10 is connected to the outer end of the spindle and the inner end of said spindle is formed with notches forming teeth 11 located adjacent the opening 5. 75 The toothed end of the spindle may be held properly centered within the casing by a collar 12 thereon which engages the wall of the casing.

A latch 13 is pivotally mounted in the 80 slot 4 and has a laterally extending slot 14 therein the width of which is less than the diameter of the opening 5. When the latch is in one position in the slot 4 it partly covers the opening 5, as shown in Fig. 2. 85

The reamer or other tool to be used with the instrument, and which has been shown generally at 15, is provided with a cylindrical head 16 adapted to fit snugly within the opening 5 and having an annular groove 17 90 the width of which is approximately equal to the width of the slot 4. Teeth 18 are formed on the free end of the head 16 and are designed, when the tool is in position within the opening 5, to mesh with the teeth 11. When the tool is in place the latch 13 can be swung within the slot 4 until the walls of the slot 14 in the latch enter the groove 17, thus holding the tool against withdrawal from the opening 5 and maintaining the teeth 18 in mesh with the teeth 11. 100

It will be apparent that the instrument can be held in one hand and while so held the knob 10 can be rotated. This will cause the spindle 6 to transmit rotary motion 105 through the teeth 11 to the teeth 18 and tool 15. Thus the tool, although extending at right angles to the spindle, will be driven positively and will give the operator as delicate a sense of touch as though an ordinary 110 reamer or the like were used. Because of the small size and lightness of the instru-

ment it can be manipulated readily and, as before stated, will permit a mouth mirror to be used while the canals of the posterior teeth are being reamed or cleaned. Importance is attached to the fact that the tool has a set of gear teeth formed integral therewith as a considerable saving of space is thus effected. The tool can be removed readily, as will be obvious, by swinging the 10 latch out of engagement therewith.

What is claimed is:—

A dental instrument including a casing having a rounded end provided with a flat side having a radially extending bearing 15 opening, there being a counterbore in the other end of the casing, a tool having a cylindrical head bearing within the opening and provided at its inner end with gear teeth, means for engaging the head to hold it 20 in the opening, a spindle insertible longi-

tudinally into the casing from the counterbored end thereof and having a collar seated in the counterbore, a second collar on the spindle, gear teeth at one end of the spindle and close to said second collar, said teeth meshing with the teeth on the head, a knob at one end of the spindle for rotating it, and a nut detachably seated in the counterbore and adjustable against the first mentioned collar to thrust the spindle longitudinally 25 and hold the teeth of the spindle in mesh with the teeth on the head.

In testimony that I claim the foregoing as my own, I have hereto affixed my signature in the presence of two witnesses.

WALLER E. PEARL
